UNITED STATES PATENT OFFICE

101,537

DESIGN FOR A CASING FOR AN OIL BURNER

Malcolm R. Knox, Hartford, Conn., assignor to
The Silent Glow Oil Burner Corporation, Hartford, Conn., a corporation of Connecticut

Application June 23, 1936, Serial No. 63,443

Term of patent 14 years

To all whom it may concern:

Be it known that I, Malcolm R. Knox, a citizen of the United States, residing at Hartford, county of Hartford, and State of Connecticut, have invented a new, original, and ornamental Design for a Casing for Oil Burners, of which the following is a specification, reference being had to the accompanying drawing forming a part thereof.

Fig. 1 is a perspective view shown on an enlarged scale of a casing for an oil burner, showing my new design;

Fig. 2 is a top plan view; and

Fig. 3 is a side elevational view thereof.

I claim:

The ornamental design for a casing for an oil burner, substantially as shown.

MALCOLM R. KNOX.
